UNITED STATES PATENT OFFICE.

MARTIN H. LEARNARD, OF DANVILLE, ILLINOIS.

FURNITURE-SPRING.

SPECIFICATION forming part of Letters Patent No. 237,557, dated February 8, 1881.

Application filed December 31, 1880. (No model.)

To all whom it may concern:

Be it known that I, MARTIN H. LEARNARD, of Danville, in the county of Vermillion and State of Illinois, have invented certain new and useful Improvements in Furniture-Springs; and I do hereby declare that the following is a full, clear, and exact description of the invention, which will enable others skilled in the art to which it appertains to make and use the same, reference being had to the accompanying drawings, which form a part of this specification.

Figure 1 is a perspective view of one of my improved springs detached, and Fig. 2 is a view of a set of my improved springs secured in position.

Similar letters of reference indicate corresponding parts in both figures.

This invention relates to coiled springs for beds and for upholstering purposes; and it consists in providing such springs with a peculiarly-shaped base-coil, which shall give them a firm support and prevent them from sagging or tilting over, as will be hereinafter more fully described, and particularly pointed out in the claim.

In the drawings hereto annexed, A represents one of my improved springs, the body of which, B, is of the usual and well-known conical spiral form.

The bottom or base coil, C, is made rectangular in shape, as shown, and sufficiently large to form a firm and solid support for the spring. When the latter is adjusted in its proper posi-

tion, as shown in Fig. 2, staples D are driven 35 at the angles of the base-coil, thus precluding any possibility of its sagging or tilting over, or becoming otherwise displaced.

When a suitable number of my improved springs have been adjusted in an article of 40 furniture, I prefer to connect the upper coils of each section of four springs by coiled springs E, arranged diagonally across each other and hooked or otherwise secured to the upper coils of the springs A, to which increased stability 45 is thus given without interfering with their elasticity.

I am aware that a furniture-spring having an elongated or elliptical base-coil is not new, and such I disclaim. A rectangular base-coil, 50 as herein shown, not only renders a firmer support, but is also capable of being more securely attached by staples driven at its corners.

Having thus described my invention, I claim and desire to secure by Letters Patent of the 55 United States—

The combination, with a set of four furniture-springs having rectangular base-coils, of a pair of diagonal coiled springs, arranged across each other and connected to the upper coils of the 60 main springs, as set forth.

In testimony that I claim the foregoing as my own I have hereto affixed my signature in presence of two witnesses.

MARTIN H. LEARNARD.
